CLAIM

The ornamental design for a spinal implant, as shown and described.

DESCRIPTION

FIG. 1 is a top, right, front isometric projection of a spinal implant showing our new design;

FIG. 2 is a front elevation view of the spinal implant of FIG. 1;

FIG. 3 is a rear elevation view of the spinal implant of FIG. 1;

FIG. 4 is a left side elevation view of the spinal implant of FIG. 1;

FIG. 5 is a right side elevation view of the spinal implant of FIG. 1;

FIG. 6 is a top plan view of the spinal implant of FIG. 1; and, FIG. 7 is a bottom plan view of the spinal implant of FIG. 1.

1 Claim, 5 Drawing Sheets
